UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

PRESSURE-REGULATING MECHANISM.

Application filed March 28, 1919. Serial No. 285,715.

To all whom it may concern:

Be it known that I, FREDERICK M. FURBER, a citizen of the United States, residing at Revere, in the county of Suffolk and State of Massachusetts, have invented certain Improvements in Pressure-Regulating Mechanisms, of which the following description, in connection with the accompanying drawings, is a specification, like reference characters on 10 the drawings indicating like parts in the several figures.

This invention relates to mechanism for controlling the pressure between automatically actuated tools for operating upon shoes 15 and the work treated by them, and in particular to mechanisms for controlling the pressure between the tools and the work in automatic edge-setting or burnishing machines.

20 In machines of the general type referred to, the shoe is ordinarily clamped on a jack and presented to the tool which is moved over the surface to be treated by automatically produced relative movement between 25 the tool and the work, and means are provided for producing pressure between the work and tool as the two are relatively moved.

To secure uniform results throughout the 30 portions of the work treated by the tool, the pressure between the work and tool should remain substantially constant throughout the portions of the work treated. Owing to the varying curvature of the surface treated 35 by the tool, however, it is found that the pressure between the work and the tool will vary along different portions of the work, and, since the quality or character of the work done will directly depend upon the 40 pressure existing between the work and tool, non-uniform and, in some cases, unsatisfactory results are secured. The lateral or side portions of the forepart edge of a shoe, for example, are nearly flat or straight in whole 45 or in part, the toe is much more curved, and, in some special styles of shoes, may be quite sharp, while the contour from the forepart to and along the shank presents a more or less abrupt reverse curve. These various 50 contours of the work succeed one another so rapidly as the work and the tool are relatively moved to present different portions of the work to the action of the tool that the known arrangements involving springs and

weights are not capable of responding to the 55 demands of the work and fail to maintain a uniform pressure. On the other hand, such variations of pressure as do take place are unrelated to the necessities of the work and produce non-uniform effects in different 60 parts of the shoe or sole edge.

An important feature of the present invention consists of means for maintaining the pressure between the work and the tool constant as the work and the tool are relatively moved, so that substantial uniformity in the finished product may be secured. In the machine shown a fluid pressure means is provided arranged to exert uniform pressure on the tool irrespective of its position. 70

While the pressure maintained between the work and the tool may be suitable for the treatment of some portions of the work, or even most of it, it may not be adapted for the treatment of other portions. At the 75 junction of the forepart and shank, for example, where the curve of the forepart merges into or unites with the curve of the shank, there is usually a corner more or less sharp or abrupt, which is liable to be crushed 80 or deformed by the pressure between the work and the tool, since it is not able to stand the full pressure found suitable to finish or set the sole edge along the more straight or less abruptly curved portions. 85

Another important feature of the present invention, therefore, consists of novel means for automatically controlling the application of pressure between the work and the tool at a predetermined part or parts of the 90 work. In the machine shown means operated in time relation to the relative traverse of the work and tool is provided to open the control valve of the fluid pressure means.

Other features of the present invention 95 comprise certain arrangements and novel combinations of parts which, in addition to the features above set forth, will be herein described and definitely set forth in the claims.

In the drawings which show the present invention embodied in the automatic edge setter described in the patent to Keall, Gouldbourn & Jerram No. 1,078,684:

Figure 1 is a side elevation of a machine, 105 some of the parts being broken away for clearness of illustration;

Fig. 2 is a detached sectional detail on an

enlarged scale of the pressure or reaction mechanism for controlling the pressure between the work and the tool;

Fig. 3 is a front view, partly in section and 5 with parts broken away, showing the pressure controlling mechanism;

Fig. 4 is an enlarged section on the line 4—4 of Fig. 1, some of the parts being omitted and others broken away for clearness of illustration.

The tool which, in the present illustrated form of the invention consists of an edge setting tool 10, is carried in the head 11 in which it is vibrated in a substantially horizontal plane to act upon the edge of a shoe *a*, as indicated in Fig. 1. The head 11 is supported by the link members 12, 13, the former of which is pivotally connected to the pressure lever 14, and the latter of which is also pivotally connected to the pressure lever 14 by means of a bell crank 15 which is pivoted on the pressure lever and has its extremities pivoted to the member 13 and a link 16, the lower end of which is connected pivotally to the main frame of the machine at 17, Fig. 1. The pressure lever 14 is pivotally supported on the main frame of the machine at 18, and rotation of the pressure lever about its pivot 18 causes the tool 10 to move to the right or left in Fig. 1. The members 12, 13, 14, 15 and 16 constitute a parallel-motion mechanism which may be substantially as more fully described in the Patent No. 1,078,684 hereinbefore referred to.

The shoe *a* is clamped in a jack 19 mounted on a shaft 20 which is controlled by mechanism which permits it to move in a horizontal plane and to turn about a vertical axis, as described in said patent. A cam 21 on the shaft 20 is automatically rotated and translated in a horizontal plane in order to turn the shoe from one side to the other and keep its edge presented to the tool 10. During the operation of the machine the shoe and tool are relatively moved to present different portions of the sole edge to the action of the tool and since the mechanism for accomplishing these results is clearly described in the patent referred to and in all substantial respects the present embodiment of these features is the same as in said patent, further description is unnecessary and reference is made to said patent for a more full disclosure thereof.

The pressure lever 14 carries a toothed segment 22 which engages a rack 23 mounted on or actuated from a piston 24. The piston 24 moves in a cylinder 25 which is mounted on the end of a rod or plunger 26. The rod or plunger 26 and the rack 23 are supported for sliding movement in suitable supports, such as the casing or guides 27. The rod or plunger 26 has a reduced portion 28 where it passes through the guide

or support 27 and a channel 29 leads from the outer surface of the rod or plunger 26 inward to the interior of the cylinder 25 which, as before explained, is carried by the plunger or rod 26.

An inlet pipe 30 and an outlet pipe 31 are in communication with the casing adjacent the reduced portion 28 of the rod or plunger 26, the construction being such that the fluid which may be preferably oil under pressure, will flow freely from the inlet pipe 30 into the space surrounding the contracted portion 28 of the rod or plunger 26 and flow through the opening 29 into the cylinder 25 below the piston 24. The outlet pipe 31 has a pop valve 32, the stem 33 of which is forced up by a spring 34 interposed between the valve casing and an adjustable nut 35 threaded to the upper portion of the valve stem 33, the construction being such that by adjustment of the nut 35 upon the valve stem, the tension of the spring 34 may be varied to hold the valve 32 to its seat at any desired pressure. The valve 32 opens downwardly and the outlet pipe 31 communicates with the valve chamber above the valve 32, as indicated in Fig. 3, so that by adjustment of the spring 34, the pressure necessary for opening the valve 32 to permit outflow of the fluid, may be adjusted as desired. The fluid pressure may be obtained from any suitable source, either a head of fluid or from a pump.

The rod or plunger 26 may have its lower end projecting into a dashpot 36 for absorbing the shock when the pressure is taken off the tool, as will hereinafter more fully appear. Connected to the rod or plunger 26 is a manually operated controlling lever 37 which may be pivoted at 38 to a part fixed to the machine frame and connected by a link 39 with a collar 40, Fig. 2, secured to the rod or plunger 26. Interposed between the collar 40 and a shoulder 41 formed in the casing or support 27, is a spring 42 normally acting to move the rod or plunger 26 downwardly but yieldable on movement of the controlling lever 37 contraclockwise, viewing Figs. 1 and 2, to permit the rod or plunger 26 to be moved upwardly.

From the construction described, the rod or plunger 26 and its associated cylinder and piston, constitutes a two-part pressure transmitting element acting when the controlling lever 37 is turned contraclockwise as described, to move the tool and work into pressure relation, and the valve controlled fluid pressure, acting through the cylinder 25 and piston 24, serves to maintain such pressure constant and uniform, as defined by the tension of the spring 34.

At certain portions of the work it may be desirable to relieve the pressure between the work and the tool. This may occur at any part of the work or along the sole edge,

but is particularly the case along that portion where the curves of the forepart and the shank merge into each other especially where certain forms of freak styles are being treated as, for instance, spade shank shoes. To effect this relief of the pressure at a desired part of the shoe, the present embodiment of the invention provides a rod 43 mounted for sliding movement in a guide 44 and preferably arranged in line with the upper end portion of the valve stem 33. The rod 43 is adapted to be reciprocated longitudinally by a rack and pinion which, in the present instance of the invention, comprises a series of rack teeth formed on the rod 43 which are engaged with the idler pinion 45 which, in turn, is actuated from the toothed segment 46 by the eccentric 47 on the shaft 20, as indicated in Fig. 4. In the present instance of the invention the eccentric 47 has an eccentric strap 48 embracing the same and from the strap 48 extends the arm 49 jointed at 50 to the toothed segment 46, the construction being such that as the shaft 20 is rotated the rod 43 will be reciprocated in its guides.

The rod 43 may have secured thereto means for contacting with the upper end of the valve stem 33 as the rod 43 is reciprocated to thereby open the valve 32 and release or modify the pressure between the work and tool. In the present instance of the invention the rod 43 has adjustably secured thereto the two cams 51 one of which may act upon the valve stem to open the valve 32 and relieve the pressure between the tool and the work as the tool acts upon or passes along a portion of the sole edge at the outside of the tread surface and the other of which may similarly act to relieve the pressure between the tool and the work as the tool moves along a portion of the sole edge at the inner side of the tread surface. By suitable variation in the form or character of the means for automatically acting upon the valve stem 33, it is possible to determinately vary the pressure between the tool and the work at any part of the work or modify or relieve the pressure altogether.

The operation of the machine is as follows:

By suitable means, such as a pump or head, the fluid in the cylinder 25 is maintained under a pressure determined by the adjustment of the spring 34. As the shoe is turned from one side to the other by the shaft 20, as more fully described in the patent heretofore called to attention, slight movements to the right or left as seen in Fig. 1 of the point of contact of its sole edge with the tool 10 will occur, the pressure lever 14 moving correspondingly to maintain the contact. In heretofore existing machines of this

general type, such movements of the tool carrying mechanism have altered the pressure of the tool on the work. In the present invention, however, the valve 32 is set to maintain the pressure in the cylinder 25 which will give the desired reaction between the tool and the work through the piston and rack and segment. When a slight movement of the pressure lever 14 allows the piston to yield upwardly, the valve 32 closes and the pressure of the fluid moves the piston 24 to maintain uniform pressure between the work and the tool. When the pressure lever 14 moves in the opposite direction the piston 24 is forced downwardly thereby opening the valve 32 which has been previously set or adjusted, and the pressure between the work and tool remains unchanged.

Thus, regardless of the position of the pressure lever 14 and of the piston in the cylinder, substantially uniform pressure is maintained in the cylinder and between the work and the tool.

When the controlling lever 37 is released and swung to the right or clockwise in Figs. 1 and 2, the piston will move to the upper head of the cylinder and the whole system shown in Fig. 2 will be moved to the left by the spring 42, and the tool will be moved back from the shoe.

When a predetermined part of the work is presented to the tool whereat the pressure is to be modified or entirely relieved, the automatic action of the cams or other parts carried by the rod 43 act upon the end of the stem 33 to automatically depress or open the valve and relieve the fluid pressure in the cylinder and, perforce, the pressure between the shoe and the tool.

Having described my invention, what I claim as new and desire to secure by Letters Patent of the United States is:—

1. In a machine for operating upon shoes including mechanism for maintaining uniform pressure between a tool and work having abrupt changes of outline, the combination of a work support, a tool movable into different positions by the changing outline of the work, means for producing relative movement of the work and tool to transfer the point of operation of the tool along the changing outline of the work, and means for maintaining unvarying pressure between the work and the tool as the point of operation of the tool is moved along the abruptly changing outline.

2. In a machine for operating upon shoes, the combination of a tool, means for producing relative movement between the shoe and tool to transfer the point of operation of the tool along the shoe, means for producing pressure between the shoe and tool, and means for maintaining the pressure between

the shoe and tool of substantially unvarying amount as the shoe and tool are relatively moved.

3. In a machine for operating upon shoes, the combination of a work support, a tool, means for producing relative movement of the work and tool to transfer the point of operation of the tool along the shoe; pressure producing means for causing pressure between the work and tool as they are relatively moved, and means automatically responsive to the changing conditions of the work for maintaining the pressure between the tool and the work constant as they are relatively moved.

4. In a machine of the class described, the combination of a work support, a tool, means for producing relative movement between the work and tool that the tool may act along the changing contour of the work, pressure producing means acting through the tool to produce pressure between the work and tool including pressure controlling means for automatically maintaining the pressure constant between the work and tool as the work and tool are relatively moved so that abrupt changes of contour are brought opposite the tool.

5. In a machine of the class described, the combination of a work support, a tool movable into different positions by the changing contour of the work as the tool and work are relatively moved to present different portions of the work to the action of the tool, and pressure producing and controlling means acting automatically to maintain an unchanging pressure between the work and tool as they are relatively moved in spite of sharp breaks in the contour of the work.

40 6. In a machine of the class described, the combination of a work support, a tool movable into different positions by the work as the work and tool are relatively moved to present different portions of the work to the action of the tool, pressure producing means responsive to the movements of the tool, and means for maintaining the pressure produced by the pressure producing means constant as the tool is moved into different positions by the work.

7. In a machine of the class described, the combination of a work support, a tool, means for producing pressure between the work and tool as they are relatively moved to present different portions of the work to the action of the tool, and means acting automatically for maintaining the pressure constant throughout a portion of the work and for relieving the pressure at predetermined portions of the work.

60 8. A machine of the class described, comprising, in combination, a work support, a tool for acting along different portions of the work as the work and tool are relatively moved, fluid pressure means for producing

pressure between the work and the tool, and means acting automatically to change the pressure between the work and tool at predetermined portions of the work.

9. In a machine of the class described, the combination of a shoe support, a tool, pressure producing means acting through the tool to produce pressure between the shoe and tool as they are relatively moved to present different portions of the shoe to the action of the tool, and means for removing the pressure between the shoe and tool at certain portions of the work.

10. In a machine of the class described, comprising, in combination, a work support, a tool for acting along different portions of the work as the work and tool are relatively moved, fluid pressure means for producing pressure between the work and the tool, and automatic means for modifying the pressure produced by the pressure producing means at a predetermined portion of the work.

11. In a machine of the class described, the combination of a work support, a tool for acting upon different portions of the work, and fluid actuated means for maintaining unvarying pressure between the work and the tool as the tool and work are relatively moved.

12. In a machine of the class described, the combination of a work support, a tool for acting upon different portions of the work, fluid actuated means for maintaining unvarying pressure between the work and the tool as the tool and work are relatively moved, and automatic means acting through the fluid means to modify the pressure between the work and tool at a predetermined part of the work.

13. A pressure regulating device for edge setters, comprising, in combination, a two part pressure transmitting element, a tool, connections between the tool and the two part pressure transmitting element, means for exerting pressure through said two part element to the tool, and means acting automatically for permitting relative movement of the two parts of the transmitting element for controlling the pressure exerted by the pressure means.

14. A pressure regulating device for edge setters, comprising, in combination, a two part pressure transmitting element, a tool, connections between the tool and the two part pressure transmitting element, fluid actuated means for exerting pressure between the work and the tool through the two part element, and means for maintaining the fluid pressure constant.

15. In a machine of the class described, the combination of a work support, a tool for acting along the edge of a shoe as the tool and shoe are relatively moved, a pressure transmitter for maintaining pressure

- between the edge of the shoe and tool and movable by the tool to different positions as it conforms to the changing contour of the shoe, and automatic means for maintaining 5 the pressure between the shoe and tool invariable as the transmitter is moved by the tool.
16. In a machine of the class described, the combination of a work support, a tool, 10 fluid pressure means for producing pressure between the work and tool as they are relatively moved to transfer the point of operation of the tool along the work, and pressure relieving means acting automatically 15 to relieve the pressure between the work and tool at predetermined portions of the work.
17. In a machine of the class described, the combination of a work support, a tool, 20 means operable at will for moving the tool and work into operative relation that the tool may act along different portions of the work as the tool and work are relatively moved, means for producing pressure between the work and tool when they are in 25 operative relation, and means responsive to the varying contour of the work for maintaining the pressure between the work and tool of constant amount as the work and tool are relatively moved.
- 30 18. In a machine of the class described, the combination of a work support, a tool, fluid pressure actuated means for maintaining pressure between the work and tool as they are relatively moved to transfer the 35 point of operation of the tool along the work, and a valve for maintaining the pressure exerted by the fluid pressure actuated means of equal amount as the work and tool are relatively moved.
- 40 19. In a machine of the class described, the combination of a work support, a tool, fluid pressure actuated means for maintaining pressure between the work and tool as they are relatively moved to transfer the 45 point of operation of the tool along the work, a valve for maintaining the pressure exerted by the fluid pressure actuated means of equal amount as the work and tool are relatively moved, and means for automatically 50 opening the valve to modify the pressure between the work and tool at a predetermined portion of the work.
20. In an edge setter, the combination of a tool for acting along the edge of a shoe, 55 pressure means for producing pressure between the shoe and tool as they are relatively moved, means for determinately adjusting said pressure, and means acting automatically for relieving the pressure of the tool 60 against the edge of the shoe at predetermined portions of the shoe.
21. In an edge setter, the combination of a tool for acting along the edge of a shoe, a two part plunger for moving the tool into 65 contact with the shoe, pressure exerting means for relatively moving the two parts of the plunger for producing pressure of the tool against the shoe, and automatic means for relieving the pressure of the tool against the shoe at a predetermined portion 70 of the shoe.
22. In a machine of the class described, the combination of a work support, a tool, means for producing pressure between the shoe and tool as they are relatively moved 75 to transfer the point of operation of the tool along the shoe, means for determinately adjusting the amount of pressure to be exerted between the shoe and tool, and means for automatically maintaining the adjusted 80 pressure unchanged as the shoe and tool are relatively moved.
23. In a machine of the class described, the combination of a work support, a tool, 85 means for producing pressure between the shoe and tool as they are relatively moved to transfer the point of operation of the tool along the shoe, means for determinately adjusting the amount of pressure to be exerted between the shoe and tool, and means for 90 automatically releasing the pressure between the shoe and tool at a predetermined part of the shoe.
24. In a machine of the class described, a 95 shoe jack, a tool, means for carrying the point of operation of the tool along the work, and automatic means for maintaining constant pressure between the tool and work comprising a cylinder and a piston one of which is connected to one of the tool or jack, 100 and the other of which is connected to the frame of the machine, and means for maintaining constant pressure in the cylinder irrespective of the position of the tool or jack, respectively.
25. In a machine of the class described, a 105 shoe jack, a tool, means for carrying the point of operation of the tool along the work, and automatic means for maintaining constant pressure between the tool and work comprising a cylinder and a piston one of which is connected to the tool and the other of which is connected to the frame of the machine, and means for maintaining constant pressure in the cylinder irrespective of 110 the position of the piston, comprising a pop valve adjustable to maintain any desired pressure.
26. In a machine of the class described, a 120 shoe jack, a tool, means for carrying the point of operation of the tool along the work, and automatic means for maintaining constant pressure between the tool and work comprising a cylinder and a piston one of which is connected to the tool and the other 125 of which is connected to the frame of the machine, and means for maintaining constant pressure in the cylinder irrespective of the position of the piston, comprising a pop valve adjustable to maintain any desired 130

pressure, and means operated in time relation to the relative traverse of the work and tool to release the pop valve at a predetermined point.

- 5 27. A machine of the class described, comprising, in combination, a work support, a tool for acting along different portions of the work as the work and tool are relatively

moved, fluid pressure means for producing pressure between the work and the tool, and 10 means acting automatically to control the application of pressure by one to the other.

In testimony whereof I have signed my name to this specification.

FREDERICK M. FURBER.
